ATTORNEY

UNITED STATES PATENT OFFICE.

SIDNEY A. KELLER, OF NEW YORK, N. Y., ASSIGNOR TO MARCUS T. GOLDSMITH, OF NEW YORK, N. Y.

DESIGN FOR AN ORNAMENTAL SHIELD.

SPECIFICATION forming part of Design No. 35,884, dated April 29, 1902.

Application filed April 8, 1902. Serial No. 101,961. Term of patent 7 years.

To all whom it may concern:

Be it known that I, SIDNEY A. KELLER, a citizen of the United States, residing at New York, borough of Manhattan, county of New York, and State of New York, have invented and produced a new and original Design for Ornamental Shields for Attachment to Leather and Ebony Goods, of which the following is a specification, reference being had to the drawing forming a part thereof and showing an ornamental shield bearing my new design.

The leading or characteristic feature of my design consists of the outline or contour of the shield, the upper and lower ends of the latter bearing fanciful scrolls into which merges a fanciful border, a portion of the central field of the shield being left plain and

the remainder bearing the figure of a female head. As shown in the drawing, the shield has an irregular outline, the upper end or corner being ornamented with the scroll A and the lower end with a scroll B, into which merges a border C. One portion D of the central field is left plain, the remaining portion bearing the figure of a female head E.

What I claim is—

The design for an ornamental shield, substantially as herein shown and described.

Signed at New York, in the county of New York and State of New York, this 7th day of April, A. D. 1902.

SIDNEY A. KELLER.
